ATTY.

UNITED STATES PATENT OFFICE.

GUY D. ATKINS, OF ERIE, PENNSYLVANIA.

DEVICE FOR EXHIBITING SHOES.

SPECIFICATION forming part of Letters Patent No. 235,402, dated December 14, 1880.

Application filed July 9, 1880. (No model.)

To all whom it may concern:

Be it known that I, GUY D. ATKINS, a citizen of the United States, residing at Erie, in the county of Erie and State of Pennsylvania, have invented certain new and useful Improvements in Devices for Exhibiting Shoes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to the construction of a clamping device for use on shoe-boxes in stores for holding a shoe thereon for exhibition or display, and also to serve as a pull for drawing said box out of its place on the shelf, 20 in the same manner as the pull on a drawer is used.

My invention consists in improvements in the construction of the device named above.

25 My improved device for exhibiting shoes is shown in the accompanying drawings, as follows:

Figure 1 is a top view of the clamp, and shows it clamping a shoe. Fig. 2 is a side view or elevation in outline. Fig. 3 is a longitudinal section taken vertically through Fig. 2.

30 The parts of the device are as follows: A body or base, A, with standards A' A', a clamping-lever, B, with jaw B' and curved handle B'', a spring, S, and pivot-pin P. The part A A' A' is one piece of metal, and so is the part B B' B''.

The standards A' A' have their inner faces curved or concaved, as seen at a a, to form a barrel-like space for containing the spring S, 40 which is a common spiral formed of wire. Between the standards is sufficient space for the lever B.

The base-piece, A is provided with suitable screw-holes for screwing the same to the box-panel.

45 The lever B is provided at one end with a jaw, B', and at the other with a curved handle, B'', to form a finger-piece, behind which the finger can be inserted to draw out the box, thus serving the same as a pull on a drawer. Through the head or jaw part B' is an open-

ing, b, to enable a screw to be inserted in the base-piece A below the jaw B' without removing the lever from its bearings.

Of course the bed-piece A could be made 55 sufficiently long to bring the screw-opening in it outside the end of the jaw of the lever; but such a construction would require the use of more material, and as the devices are of such a nature that they have to be cheap in order 60 to be generally used, the saving of metal is greatly desirable.

The hole in the part I call the "jaw" is cast in, and requires no labor to effect it, and, in fact, as it requires so much less metal in the 65 jaw, it is also a saving. This hole may be quite large, so as to leave only a small rim of metal to form the jaw, and thus effect quite a saving in the metal used, and also giving a light and finished appearance to the device. 70

The part of the lever which serves as a bearing for the spring S should be on a curve, substantially as shown in Fig. 3, in order to properly bear upon the spring as the lever is moved through its arc of motion.

75

What I claim as new is as follows:

1. A device for exhibiting shoes, as described, consisting of a bed-piece, A, with standards A' A', having concaved inner faces, forming a barrel-like space for the clamping-spring, in combination with the lever B, with jaw B', substantially as shown.

2. In a clamping device, the combination, with a bed-piece, A, having pivot-standards and screw-openings therein, of a clamping-lever, B, with jaw B', having an opening, b, for giving access through said jaw to one of said screw-openings, substantially as and for the purposes mentioned.

3. In a clamp device for exhibiting shoes, as 90 described, the combination, substantially as shown, of the following elements: a bed-piece, A, with pivot-standards A' A', having concaved or grooved inner faces, forming a recess to contain the clamping-spring, a clamping-lever, B, with jaw B', having an opening, b, for access through it to the bed-piece, for the purposes named, and a spiral clamping-spring, S, for actuating said lever, and located within the recess named.

100

4. In a clamp device for exhibiting shoes, as described, or for other purposes, the combina-

the article, and for holding the article in position, substantially as shown, of the following elements: a bed-piece, A, with pivot-standards A' A', having concaved or grooved inner faces for containing an actuating-spring, a spiral actuating-spring within said recess, a clamping-lever pivoted on said standards and having a curved face for bearing against said spring, and a jaw, B', upon one end thereof,

for properly holding the article to be clamped between it and the bed-piece.

In testimony whereof I affix my signature in the presence of two witnesses.

GUY D. ATKINS.
